United States Patent

Des. 235,374
Patented June 10, 1975

235,374

COMPACTOR

Salvatore F. Aiello, Racine, Wis., assignor to
Loed Corporation, Wausau, Wis.

Filed Oct. 30, 1972, Ser. No. 302,137

Term of patent 14 years

Int. Cl. D15—04

U.S. Cl. D60—1

FIG. 1.

FIG. 2.

FIG. 1 is an elevational view of my design for a compactor;

FIG. 2 is a front elevational view of my compactor as shown in FIG. 1;

FIG. 3 is a left side elevational view of my compactor design shown in FIG. 1;

FIG. 4 is a rear elevational view of my compactor shown in FIG. 1;

FIG. 5 is a right side elevational view of my compactor design shown in FIG. 1; and

FIG. 6 is a fragmentary sectional view taken along the line 6-6 of FIG. 2.

I claim:
The ornamental design for a compactor, as shown.
